IRRIGATING APPARATUS

Rodney S. Kennison, Los Angeles, Calif.

Application December 23, 1938, Serial No. 247,347

2 Claims. (Cl. 128—227)

My invention relates to improvements in irrigating apparatus, the primary object being to provide improved means by which the colon or vagina can be most effectively and safely treated by irrigation. More particularly this invention is the subject matter of a continuation in part of my companion application filed July 27, 1935, Serial Number 33,448, from which the improved construction of applicator or nozzle therein disclosed was claimed. The present application is directed more particularly to features relating to the table construction; the flexible means having sufficient rigidity for automatically holding the nozzle or applicator in adjusted position when applied in use or out of the way when removed from applied position; the specimen take off; the improved means for indicating pressure within the colon or other body orifice; the improved means for indicating the number of times the apparatus is used; the improved sterilizing means; and various other improvements, all of which will be set forth in the following specification and of which the accompanying drawings form a part.

In the drawings, Fig. 1 is a perspective view of my improved apparatus, a portion of the table being broken away to more clearly disclose the platform; Fig. 2 is an end elevation looking at the foot end of the table; Fig. 3 is an elevational center section of a detail showing the flushing receptacle in the surface of the table; Fig. 4 is a diagrammatic view showing the meter and its method of application to the irrigating apparatus for indicating the number of times the apparatus is operated; Fig. 5 is a diagrammatic plan of the irrigating apparatus removed from the table; Fig. 6 is an elevation of a detail showing the nozzle or applicator for insertion in a body orifice, the flexible egress duct for holding the nozzle adjusted for use or removed out of the way and the swivel by which the egress duct can be swung away clear of the table; Fig. 7 is a side elevation partly in central vertical section of my improved nozzle which is applied to the free end of the flexible egress duct, and Fig. 8 is a transverse section of Fig. 7, taken on line 8—8.

In the drawings, A represents my improved table having a flat top 10, supported by suitable frame work including the sides 10 and 11, ends 12 and 13 and legs 14. Arranged in the foot end of the table is an elevated platform 15, which has sufficient horizontal area so that a patient can mount the same while facing the table and easily turn around and sit on the top 10 while the feet remain supported by the platform. Across the

foot end of the table top above the inner end of the platform is a drop panel 16, which is hinged at 17 to the end of the flat top 10 and adapted to swing down into substantially vertical position clear of the inner end of the platform. When raised into horizontal position it lies substantially in the plane of the top and is so held by suitable spring catches 18, which engage the side arms 19 of the table (see Fig. 2). The flexible cord or chain 20 fastened to the spring catches facilitates the operator in disengaging both catches simultaneously to release the panel. The side arms 19, in addition to serving as supports for the free end of the panel also function as holders for bracing the patient while in the act of mounting or dismounting the table. The surfaces of the table top and panel may be covered with suitable padding 21. Thus when the panel is raised into superior position sufficient padded area is provided to comfortably support the patient while lying flat upon the table.

Immediately back of the drop panel 16, the table top has a flushing receptacle or bowl 22, recessed downwardly therein, which is closed when desired from above by the removable cover 23. When this cover is in place and the drop panel raised into horizontal position a substantially continuous flat table top is provided. During and after treatment the cover can be removed and the flushing receptacle used while the patient is lying flat or assumes sitting posture. The bottom of the flushing receptacle is connected with a sewer waste duct 24 and the upper portion of the bowl has a tangentially directed nozzle 24' which is connected with a suitable source of liquid such as provided by the overhead reservoir container B. This container has an outlet duct 25 which is controlled by the valve 26 on the front side of the table convenient for use by the operator.

The container B may be a transparent bowl, supported above the table by the bracket 30 on a standard 31, to produce the desired hydrostatic pressure of the liquid therein. The lower portion of the bowl has its outlet duct 25 provided with a branch 32 which is controlled by a hand operable valve 33 on the front of the table. This branch connects through a flexible tube 34 with the nozzle or applicator C as will be hereinafter described. Hot or cold liquid is supplied to the container B by duct 35, either from the valved hot liquid supply 36 or from the valved cold liquid supply 37. The valves 38 and 39 for controlling these sources of supply are placed on the front of the table convenient to the operator. A

thermometer 40 placed in the container serves to indicate the temperature of the liquid therein.

The nozzle C is formed with a hollow annulus or shoulder 41, which is shaped with a forwardly and inwardly tapering neck 42, terminating in a forwardly extending tube 43, said tube being closed at its forward extremity excepting for an orifice 44. Extending rearwardly through and spaced inwardly at its side from the tube is an inner tube 45, which flares outwardly and forms a connecting neck over which a short elastic section 46 of a tubular egress duct D engages. The flexible liquid supply tube 34 is connected with the passage between the outer and inner tubes of the nozzle by the tubular stem 47. In use the tube 43 is inserted fully in the rectum or other body orifice where it is held tightly by the resistance offered by egress duct D and with the neck and shoulder producing a tight joint to prevent leakage of the injected liquid from the body orifice. The nozzle has transverse passages 48 through the forward portion of the outer tube entering the inner tube 45 for the egress of the irrigating liquid and fecal matter from the colon or other body orifice. The temperature of the outer tube or jacket produced by the irrigating liquid received from the source of supply causes the rectal sphincter muscles and any tissue and muscle fibers in proximity to the outer surface of the outer shell to relax and stimulate circulation if the supply of irrigating liquid is hot or to contract and reduce fever if the supply of irrigating liquid is cold.

The egress duct D is a flexible tube formed by a helical flat strip 50 of spring metal or other suitable material, the convolutions thereof being tightly coiled edgewise together under spring tension to form a leak proof duct accompanied by sufficient stiffness to hold the tube adjusted in any flexed outstanding position. One end of this tube is coupled to the upper end of an elbow 51 (see Fig. 6), which is engaged by the swivel 52 on the upper end of a rigid duct 53 and the opposite end of the tube is connected with the elastic section 46. The rigid portion 53 of the egress duct is formed with a horizontal section 54 which is supported upon the front of the table by the fixed supports 55 and 56, between which a transparent sight tube 57 is inserted, through which the irrigating liquid and fecal matter therein flowing from the body orifice can be inspected. The elbow 51 is elevated above the foot of the table and its upper end swings by the swivel in substantially a horizontal plane and supports the flexible duct. When the elbow is swung out the flexible duct D is held in outstanding position away from the table so as not to obstruct the patient. After the patient mounts the table and assumes reclining position the elbow is swung in and holds the flexible duct with its nozzle inserted in the body orifice where it is automatically held tightly due to the stiffness of the duct. After use the duct can be swung clear of the table while outstanding, in which position it again remains automatically so that the patient may use the flushing receptacle or descend from the table without interference. The horizontal egress duct 54 extends to and connects with the sewer outlet duct 24 (see Fig. 5) and contains a shut off valve 55 which is opened or closed by the actuating arm 56, a reciprocable bar 57 and a rack bar 58 on the front of the table. The flexible irrigating supply duct 34 is supported near one end on the side of the flexible egress duct D by a clip 60 or other suitable means and is con-

nected at its other end to the rigid supply duct 32. A branch 61 leading to the egress duct 53 below the swivel 52 and controlled by the valve 62 (see Fig. 5) enables the operator to divert the irrigating liquid from the supply receptacle directly to the sewer connection. Also a check valve 63 in the irrigating supply duct 32 prevents any return action of irrigating liquid.

The pressure at which the irrigating liquid is administered is highly important. Too much pressure is dangerous and not enough pressure renders the apparatus inefficient. Therefore it is highly desirable to indicate in such manner as the operator and patient may both observe slight variations in pressure in the body orifice. For this purpose I have provided a super-sensitive pressure indicator E which consists of a U shaped tube 64 containing a counterpoised pressure responsive column of mercury 65 or other suitable liquid and connected at one end by the duct 66 with the egress duct 54. This tube is transparent and at least one leg thereof is exposed on the front side of the table accompanied by a suitable scale 67 which cooperates with the pressure affected column of indicating liquid to register any variations in pressure of liquid in the body orifice transmitted through the egress duct 53. This type of indicator serves to indicate the slightest variation in pressure exerted by the irrigating liquid in the body orifice.

During the use of the irrigating apparatus, specimens of fecal matter emitted from the colon or other body orifice can from time to time be diverted and removed through a branch 68 of the egress duct which is controlled by a hand operable valve 69 and connected by the flexible tubing 70 with a specimen receiving receptacle 71.

The irrigating liquid in the supply receptacle is irradiated with ultra-violet rays by the irradiating tube F, inserted in the liquid and held in place by the receptacle cover 72. Thus the tissue and fiber of the body orifice are thoroughly sterilized by the irradiant liquid. This action is augmented by the pressure of the irrigating liquid when valve 55 is closed, which tends to expand the tissue and fiber of the orifice and thus expose the same more effectively to the effects of the irradiated irrigating liquid. The circuit for the tube is shown provided with a transformer 73, a source of electric current 74, and a switch 75, located on the face of the table by which the irradiating tube can be switched on or off as desired.

For recording the number of times the table is used, a meter G, shown diagrammatically in Figs. 1 and 4 is provided. This meter cooperates with the rack bar 57 which is operated by the hand operated actuating element 58 on the front side of the table. The rack bar and its teeth are normally engaged by the spring pressed plunger 77 of a solenoid 78. Each time the plunger is withdrawn from engagement with the rack bar, by the energizing of the solenoid 78, a plunger rod 79 actuates a conventional counter 80, the digits of which may be visible through the front side of the table. When the rack bar is thus disengaged, the flush valve 56 may be manipulated into open, closed or modified position. A conventional time switch 81 of any suitable construction desired having the operating handle 82 on the front side of the table is provided, which when wound by its handle is adapted to complete an electrical circuit through and energize the solenoid 78 at the end of the period of its operation,

whereby the valve 55 may be actuated. Immediately at the end of the operating period of the time switch G, the solenoid is de-energized and the plunger is depressed into engagement with the teeth of the rack bar 57, in which position the valve 55 is prevented from functioning until the time switch is again set to repeat the operation and the recorder made to register. As it is not practical to conduct a complete irrigating operation without closing or partly closing the valve for part of the time and opening the same for the remaining period it is therefore necessary to operate the timing switch by the actuating element 82 and record the same each time the irrigating apparatus is applied in use.

An auxiliary liquid fountain receptacle 83 and douche applicating flexible tubing 84 and nozzle 85 are shown for supplemental use when desired. Also a mirror 86 is supported by the fixture 55 on the table in effective position to enable a patient lying upon the table to observe the pressure indicated by the gauge E and determined for himself or herself the proper functioning of the apparatus.

I have described the principles of operation of my invention together with the construction thereof which I now consider to represent the best embodiment thereof, but I desire to have it understood that the apparatus shown is only illustrative and that the invention can be carried out by other means and applied to uses other than those above set forth within the scope of the following claims.

I claim:

1. Irrigating apparatus, comprising a table for supporting a body to be treated, an egress duct for flushing liquid rigidly mounted upon the table, 5 an upwardly extending tubular swivel on said egress duct having a laterally extending elbow adapted to swing in a horizontal plane, an inelastic flexible duct connected with and carried by said elbow and having a freely movable extremity for application to a body orifice, said duct consisting of a spiral band having sufficient immobility when flexed and applied in use to retain the free end thereof normally in juxtaposition to said orifice without the aid of the operator, and 10 said swivel permitting said duct to be swung away from the orifice clear of the body on the table when not applied.
2. Irrigating apparatus, comprising, means for supporting a body to be treated, a swivel adjacent 20 to said supporting means rotatable about a substantially vertical axis, an inelastic flexible duct having one end supported by said swivel whereby its free end is freely movable in a horizontal plane, a nozzle on the free end of said duct for application to an orifice of the body to be treated upon said supporting means, said duct having sufficient immobility when flexed with said nozzle applied in use to retain said nozzle in juxtaposition to said orifice without the aid of the operator, or when unapplied to retain the movable 25 end thereof adjusted in outstanding position.

RODNEY S. KENNISON.
